VACUUM CLEANER

Robert C. Lampe, Springdale, Conn., assignor to
 Electrolux Corporation, Dover, Del., a corpora-
 tion of Delaware

Application July 25, 1941, Serial No. 403,970

2 Claims. (Cl. 15—16)

This invention relates to vacuum cleaners and particularly to vacuum cleaners of the so-called inside bag type having a dust separator and a motor-fan unit located in a cleaner housing.

Vacuum cleaners of this type, and their mode of use, are well known. The cleaner unit rests on runners by means of which it may be pulled over the floor or carpet. The operator generally holds the wand containing the cleaning nozzle, which is connected to the cleaner unit by means of a flexible hose, and pulls the hose to draw the cleaner unit over the floor on its runners.

The objects of the present invention are to provide a vacuum cleaner unit of the above type having side bumpers which are constructed and secured to the cleaner unit in a new and improved manner, and having a novel latching device for detachably securing the front cover to the cleaning unit, the entire construction being such that it is easily assembled and presents a neat and pleasing appearance without sharp edges or projecting parts which might scratch or dent furniture in the room which is being cleaned.

The various features and advantages of the invention may be better understood by reference to the following specification and appended claims when considered in connection with the accompanying drawing, in which:

Fig. 1 is a longitudinal side elevation of a vacuum cleaner embodying the invention;

Fig. 2 is a similar view of the cleaner unit with the side bumpers removed;

Fig. 3 is a horizontal section taken on line 3—3 of Fig. 1, showing the latch construction;

Fig. 4 is a detail section through the latch, taken on line 4—4 of Fig. 3;

Fig. 5 is a horizontal section on line 5—5 of Fig. 1, showing the means for securing the rear end of the side bumpers to the vacuum cleaner housing; and

Fig. 6 is a detail section taken on line 6—6 of Fig. 5.

The vacuum cleaner shown in the drawing is of the inside bag type and included a cylindrical housing 10 containing a dust bag 11 indicated in Fig. 3, and a motor-fan unit, not shown.

The forward end of the vacuum cleaner is provided with a cover 12 which is secured to the housing in a manner hereinafter described, providing access to dust bag 11 within the housing. Cover 12 is provided with a suitable coupling member 13 for attachment to a flexible hose 14, by which the cleaner may be pulled by the operator. The hose 14 is attached to a hollow wand 15 to which is connected the nozzle 16.

The cleaner unit rests on runners 17 by means of which it may be pulled over the floor or carpet. The upper portion of housing 10 is provided with a ridge 18. An elongated handle 19 of rubber or other suitable material is secured to the ridge 18 and to the top of housing 10 adjacent the rear end thereof, the handle forming in effect a continuation of the ridge 18. The handle is above the motor-fan compartment which is at the center of gravity of the cleaner unit. The rear of the vacuum cleaner housing 10 is closed by means of a cover 20. The construction so far described forms no part of the present invention.

The construction and mounting of the latch for detachably securing cover 12 to the front of housing 10, which is an important feature of the present invention, is best shown in Figs. 1 to 4 of the drawing. On both sides of the vacuum cleaner housing 10, at points diametrically opposite each other, the wall of said housing 10 is depressed to form a substantially rectangular longitudinal recess 22 having a bottom wall 23 as shown in Fig. 3. Countersunk in each of said recesses 22 is an elongated dished plate 24 having side flanges 25 which rest on the housing 10 when said plate is seated in recess 22.

Seated within the dished plate 24 is a countersunk latch including a securing member 27 which is riveted at 28 to the bottom of said plate 24 and to the bottom wall 23 of the recess 22, the forward end of said securing member 27 having two spaced lugs 29 which project upwardly therefrom as shown in Fig. 3. The actuating member 30 of the latch is pivoted to said lugs 29 by means of a pivot pin 31, thus permitting the actuating member to be swung up or down about its pivot 31. The latch actuating member 30 has arms 34, and a catch member 35 constituting the other element of the latch is provided with spaced depending lugs 36 which project downwardly between said arms 34 and are pivoted to the actuating member 30 of the latch by means of a pivot pin 37. It will thus be seen that the actuating member 30 of the latch is freely movable into and out of the recess 22 about the pivot 31, while the catch member 35 constituting part of the latch is pivoted to the actuating member 30 at 37 and may therefore be moved freely up and down with respect to said member 30.

The free end of catch member 35 is bent or curved downwardly to provide a lip 38 which is adapted to engage the complementary lip 39 of a spring catch member 40 which is secured as by

rivets 41 to the cover 12 within a channel-shaped rib 42 which is attached to said cover 12. The said rib 42 on the cover 12 is provided with an opening 43 directly above the spring 40 to permit the lip 38 of catch member 35 to enter said opening 43 and engage the complementary lip 39 of the spring catch member 40.

It will be understood that the cover 12 is provided with two such spring members 40 which are arranged diametrically opposite each other in the cover 12 for engagement with the respective catches of the two latch members, and that the latch members are similarly positioned on diametrically opposite sides of the cylindrical housing 10 as previously described.

The side bumpers 45 of the vacuum cleaner unit are likewise two in number and comprise elongated channel-shaped strips of metal, plastic, or other suitable material which extend horizontally along the cylindrical housing 10, said bumpers thus forming raised ridges which extend outwardly from the sides of the housing 10 throughout the length of the housing and form side continuations of the ribs 42 on the cover.

Adjacent the rear end of said housing, at diametrically opposite points in horizontal alignment with the respective latch recesses 22 and the ribs 42 of cover 12, I provide clips 47 which are secured to the face of the housing, preferably by welding. On the under or channelled faces of bumpers 45, in position to mate with the respective clips 47, I provide U-shaped ledges 48 which are adapted to be slipped beneath the clips 47 in the manner of a bayonet joint to secure the rear ends of the respective bumpers 45 to the vacuum cleaner housing 10 as shown in detail in Figs. 5 and 6.

At their forward ends the respective bumpers 45 are secured to the housing 10 of the vacuum cleaner by means of bolts 50 as shown in Figs. 3 and 4, and the face of each of said bumpers 45 is provided with an elongated rectangular slot 51 which exactly overlies the adjacent dished plate 24 and thus affords free access to the actuating member 30 and the catch 35 of the latch which is mounted in said dished plate 24 as previously described.

In securing the respective side bumpers to the vacuum cleaner housing, the rear end of each bumper, which is to the right as viewed in Fig. 1, is first adjusted in place so that the U-shaped ledge 48 slips beneath the cooperating clip 47 as shown in Fig. 5, thus locking the rear end of the bumper upon the housing 10. The forward end of each bumper is then secured in place by means of the bolt 50 as previously described. The elongated slots 51 in the forward faces of the bumpers then overlie the respective latch members, the actuating members 30 and catches 35 of said latches being freely movable through said slots 51 about their respective pivots 37 and 38 as shown in Fig. 3.

Fig. 1 shows the vacuum cleaner completely assembled and ready for use. When it is desired to remove the front cover 12, this may be accomplished instantly by inserting the finger beneath the actuating member 30 of each latch

and swinging said actuating member upwardly upon its pivot 31. Such movement of actuating member 30 causes the connected catch 35 to move toward the left as viewed in Figs. 1 to 3, thereby releasing the lip 38 of said catch from engagement with the complementary lip 39 of the cooperating spring catch member 40 in the cover 12. The catch 35, when thus released, is free to move upwardly about its pivot 37, permitting the cover 12 to be removed from the vacuum cleaner housing 10. When it is desired to replace the cover 12 the foregoing operation is simply reversed, the lip 38 of catch member 35 being pressed downwardly about its pivot 37 into engagement with the complementary lip 39 of spring catch member 40 after which the actuating member 30 of the latch is depressed against the tension of spring 40 until said actuating member 30 lies flush with the bumper 45 within the confines of the counter-sunk dished plate 24 and secures the cover by a toggle action.

Important advantages of the latching device described above, in combination with the construction and mounting of the side bumpers on the vacuum cleaner housing, reside in the simplicity of construction, assembly and operation, and in the fact that the entire device presents a neat and pleasing appearance without sharp edges or projecting parts which might scrape or dent the furniture in the room which is being cleaned. The spring tension necessary to the latching devices, in order to insure tight locking of the cover, is provided entirely by the spring catches which are mounted in the cover. This not only simplifies the construction and assembly of the latch elements, but it also enables the number of latch parts to be reduced to a minimum and to be confined within a small area adjacent the forward ends of the bumpers with which they are associated.

The invention claimed is:

1. A vacuum cleaner housing adapted to be pulled around on the floor, said housing comprising a hollow member having an opening therein, a removable cover member therefor, bumper means attached to the side of the housing and formed with a recess adjacent to said opening, and a toggle latch mounted on one of said members and adapted to engage a catch member on the other of said members, said latch being so mounted on said one of said members that when locked it lies substantially entirely within the recess formed in said bumper means.
2. In a vacuum cleaner, an open-ended housing therefor, a removable cover for the front end of said housing providing access to the interior thereof, detachable side bumpers extending longitudinally of said housing, concealed separable fastening members carried by said housing and said side bumpers respectively adapted to secure the rear ends of said bumpers to said housing, means securing the front ends of said bumpers to said housing, and cover-securing latches at the front ends of said bumpers overlying and concealing said last-mentioned securing means.

ROBERT C. LAMPE.
